US0D1017335S

(12) **United States Design Patent** (10) **Patent No.:** **US D1,017,335 S**
(45) **Date of Patent:** **** Mar. 12, 2024**

(54) **COOLING VESSEL**

(71) Applicant: **Burger Family Holdings, LLC**,
Miami, FL (US)

(72) Inventor: **Benjamin Burger**, Miami, FL (US)

(73) Assignee: **Burger Family Holdings, LLC**,
Miami, FL (US)

(**) Term: **15 Years**

(21) Appl. No.: **29/885,672**

(22) Filed: **Feb. 27, 2023**

(51) LOC (14) Cl. **07-10**

(52) U.S. Cl.

USPC **D7/608**

(57) **CLAIM**

The ornamental design for a cooling vessel, as shown and described.

DESCRIPTION

FIG. 1 is an isometric view of the cooling vessel, embodying the claimed design;

FIG. 2 is a left elevation view thereof;

FIG. 3 is a right elevation view thereof;

FIG. 4 is a front elevation view thereof;

FIG. 5 is a rear elevation view thereof;

FIG. 6 is a top plan view thereof; and,

FIG. 7 is a bottom plan view thereof.

1 Claim, 7 Drawing Sheets
